CAM VALVE FOR FLEXIBLE TUBING

Robert L. Golby, 2511 N. Duke St.,
Durham, N.C. 27704

Filed Nov. 5, 1969, Ser. No. 19,957

Term of patent 14 years

Int. Cl. D23—01

U.S. Cl. D23—19

FIG. 1 is a side elevation view of a cam valve for flexible tubing embodying my new design, the side not shown being a mirror image thereof;

FIG. 2 is a top plan view thereof;

FIG. 3 is a bottom view thereof;

FIG. 4 is a front elevation view thereof;

FIG. 5 is a rear elevation view thereof;

FIG. 6 is a cross section view taken along line 6—6 of FIG. 2; and

FIG. 7 is a cross section view taken along line 7—7 of FIG. 1.

I claim:

The ornamental design for a cam valve for flexible tubing, substantially as shown and described.
